HOLGER L. MITCHELL AND ROLF LJUNGKULL, OF MILWAUKEE, WISCONSIN, ASSIGNEES
TO HARNISCHFEGER CORPORATION, OF MILWAUKEE, WISCONSIN, A CORPORATION
OF WISCONSIN

EXCAVATOR CRANE

Application filed February 21, 1927. Serial No. 169,703.

This invention relates to excavator cranes, and although well adapted for embodiment in a power shovel the excavator crane is also adapted for universal use and may be 5 equipped with various attachments such as the clam-shell bucket, drag-line bucket, power-hoe or the like.

One of the objects of the invention is to provide an excavator crane of this character 10 wherein the operating and controlling elements are so consolidated and organized as to be well adapted to be mounted on the small platform of the so-called "truck type" of machine or in connection with other machines 15 where the platform space is limited.

In carrying out the invention in a power shovel the digging and hoisting drums are mounted on a single shaft which may be constantly rotated in one direction by an internal 20 combustion engine or other prime mover mounted on the platform. The boom hoist drum may also be mounted on the same shaft. The several drums are selectively driven and controlled in either direction on and from 25 the shaft to carry out the operation of the crowding mechanism whereby the dipper stick is advanced or retracted, to operate the hoist line whereby the dipper stick is elevated or lowered, and to operate the boom 30 hoist line whereby the boom itself is bodily raised or lowered. In conjunction with the multiple drum assembly on the single shaft the invention also proposes a novel double chain driven through the boom foot and centrally 35 of the boom, whereby the crowding mechanism may be operated and controlled in any adjustment of the boom without any alteration or adjustment of the crowding mechanism drive. This advantage is had along 40 with the advantage of a chain drive and in an organization wherein overhung gears or overhung drives are eliminated, the chain drive along the boom being centrally thereof 45 or intermediate the bearings of the shipper shaft and the bearings of the axis of the boom foot. The consolidation of the several drums on the one shaft is had in an organization employing planetary gears to rotate 50 at least several of the drums in one direction

and clutches for fixing the drums to the shaft for rotation in the other direction.

Another object resides in the provision of an excavator crane of this character which is of simple and durable construction, which is 55 reliable and effective in operation, which embodies means for tensioning the chains of the double chain shipper shaft drive and which is adapted to be manufactured at a comparatively slight expense from materials and by 60 means of facilities ordinarily available.

Other objects and advantages reside in certain novel features of the construction, arrangement and combination of parts which will be hereinafter more fully described and 65 particularly pointed out in the appended claims, reference being had to the accompanying drawings forming a part of this specification, and in which:

Figure 1 is a view in side elevation showing 70 an excavator crane embodying the present invention.

Figure 2 is a fragmentary plan view showing the drum assembly on the platform and the double chain shipper shaft drive, parts 75 being omitted for the sake of illustration.

Figure 3 is a view in side elevation of the parts shown in Figure 2.

Figure 4 is a fragmentary view illustrating 80 the reeving of the boom hoist line.

Figure 5 is a diagrammatic perspective view further illustrating this feature.

Figure 6 is a view partly in elevation and partly in section on line 6—6 of Figure 2 and illustrating the multiple drum assembly on 85 the single shaft.

Figure 7 is a sectional view on line 7—7 of Figure 3; and,

Figure 8 is a diagrammatic view illustrating 90 the pawl and ratchet arrangement for preventing the boom hoist drum from overrunning the shaft during the lowering of the boom.

Referring to the drawings the numeral 1 designates a truck which has self-laying 95 tracks 2 mounted and driven in the usual manner. On this truck 1 a platform 3 is mounted and supported, the platform 3 being adjustable or swingable in a horizontal plane about a vertical axis associated therewith and 100

with the truck 1. At the forward end of the platform 3 a boom foot socket 4 is secured and in this socket 4 a boom foot 5 in the form of a yoke is rotatably fitted. The boom foot 5 is rigidly secured to the lower end of the boom 6. A fixed pin or shaft 7 extends through alined bearings provided in the boom foot socket 4 and in the boom foot 5 to constrain the boom to swinging movement in a vertical plane and about the horizontal axis afforded by the stationary pin or shaft 7. This boom 6 is braced laterally by braces 8 connected with the boom as at 9 and having links 10 connecting the lower ends of the braces to the platform 3. One pivotal axis of each link 10 is transversely aligned with the fixed shaft 7 so that the braces 8 do not interfere with the vertical movement of the boom and yet brace the same laterally.

20 A dipper stick 11 is provided and carries a bucket or scoop 12 in the usual manner. The dipper stick 11 is made up of a pair of members 11* which are slidably fitted in saddle blocks or guides 13 pivotally mounted on the ends of a shipper shaft 14, rotatably supported in bearing brackets 15 fixed on the sides of the boom. Pinions 17 fixed on the shipper shaft engage racks 18 fixed on the members 11* of the dipper stick 11 to move the dipper stick in and out and also to coact with the guides 13 to constrain the dipper stick to proper movement.

30 An internal combustion engine 20 or other suitable prime mover is mounted on the platform 3 and has a pinion 21 fixed to its engine shaft 22, the pinion 21 meshing with a large gear wheel 23, fixed on a shaft 24 extending transversely of the platform and rotatable in suitable bearings 25 secured thereon. The angular adjustment of the platform on the truck 1 is effected and controlled from this shaft by means of a pair of clutches 26 and 27 associated with oppositely disposed beveled gear wheels 28 and 29 for selectively clutching these gear wheels to the shaft 24. The beveled gear wheels 28 and 29 constantly mesh with the beveled gear wheel 30 connected to a vertical shaft 31 journaled in bearings provided on the platform and having a pinion 32 on its lower end meshing with a ring gear 33 fixed on the truck. By engaging the clutches 26 or 27 the pinion 32 may be rotated in one or the other direction and travels around the ring gear 33 to swing the platform 3 as may be desirable. A small gear wheel 35 is fixed to the shaft 24 and meshes with a large gear wheel 36 keyed on a drum shaft 37. The drum shaft 37 extends transversely of the platform 3 and parallel to the shaft 24 and is rotatably mounted in suitable bearings 38 provided therefore on the platform. It will be understood from the foregoing that this shaft 37 is continuously rotated at a constant speed in a counter clockwise direction as

viewed in Figure 1 when the engine 20 is running. On this single drum shaft 37 all of the drums employed are mounted. As shown in Figure 6 a digging drum or crowding drum 39 is loosely mounted on the shaft 37 adjacent one end thereof; a hoist drum 40 is loosely mounted on the shaft 37 adjacent the drum 39; and a boom hoist drum 41 is loosely mounted on the shaft 37 adjacent the hoist drum 40.

70 The digging drum 39 has a sprocket wheel 42 integral therewith and from this sprocket wheel the motion is taken for rotating the shipper shaft 14 in either direction to advance or thrust forward the dipper stick or to retract the same as may be desirable during the excavating operation. In carrying out this purpose a sprocket chain 43 is engaged with the sprocket wheel 42 and is also engaged with a sprocket wheel 44 keyed on a shaft 45, journaled in bearings 46 provided at the upper ends of bracket arms 47. The bracket arms 47 have bearing openings 48 in which the ends of the fixed shaft or pin 7 are rotatably fitted whereby the arms 47 may be adjusted to tension the chain 43. This adjustment is effected and secured by tensioning screws 49 having eyes integral therewith and pivotally connected as at 50 to bifurcated lugs 51 formed on and projecting forwardly from the lower ends of the arms 47. These adjusting screws 49 extend through openings formed in the platform 3 or in a part fixed to the platform and are held in adjusted position by nuts 52 threaded on the screws and engaging the opposite sides of the platform. Rearwardly projecting extensions 54 are provided on the arms 47 beyond the bearings 46 and are connected by a transversely extending tie rod 55 held in position by nuts 56. Pins 57 or other suitable means are mounted on the ends of the shaft 7 and coact with the adjacent portions of the boom foot socket 4 to prevent axial displacement of the arms 47 on the stationary shaft or pin 7. A gear wheel 58 is keyed to the shaft 45 at a point spaced from the sprocket wheel 44 and this gear wheel 58 meshes with a similar gear wheel 59 integrally formed with or suitably secured to a sleeve shaft 60 rotatably fitted on the stationary shaft or pin 7 between the arms of the yoke of the boom foot. This same sleeve shaft 60 also has a sprocket wheel 61 integrally formed therewith or suitably fixed thereto, and with the sprocket wheel 61 a sprocket chain 62 meshes. The sprocket chain 62 extending centrally along the boom 6 and around a sprocket wheel 63 fixed to the portion of the shipper shaft lying between its bearings 15. The upper run of this sprocket chain 62 travels over a tensioning sprocket wheel 64 adjustably mounted on a bracket 65 fixed to the boom 6 and the lower run thereof travels around an idler guide sprocket 66.

also mounted on the boom 6. With this arrangement it is noted that the shipper shaft has a double chain drive through the boom foot and that the drive is of such a character that sprocket chains may be employed. The drive is transmitted through and around the axis on which the boom swings so that adjustment of the boom in no way impairs the drive. Moreover, the drive for the shipper shaft is equally effective in all adjustments and this advantage is had without making necessary any alteration of any operation or adjustment of the shipper shaft. A further important advantage resides in the fact that the sprocket chain 62 is geared to the shipper shaft between its bearings 15 thereby obviating the transmission of a drive through an overhung portion of the shipper shaft. When the dipper stick 11 is to be thrust forward the drum 39 is clutched to the shaft 37 to rotate in the same direction as the shaft 37 and at the same speed. This clutching of the drum 39 may be brought about by means of a clutch band 67 encircling an annular flange 39^a of the drum 39, one end of the band 67 being suitably connected to a spider 68 keyed to the shaft 37 along side of the drum 39, the other end of the band 67 being connected with a contracting and expanding lever 69 having a stud 70 rotatably mounted on the spider 68. This lever 69 also has a curved arm 71 extending through an opening in the spider to the opposite side thereof from the drum 39. The inner end of this arm 71 is pivotally connected to a link 72 which, in turn, is pivotally connected to a lug 73 integral with the hub 74 of a pulley 75. The pulley 75 is loosely mounted on the shaft 37 but its grooved periphery is encircled by a brake band 76 which is under the control of suitably extending and contracting means. When this brake band 76 is contracted it tends to hold the pulley 75 against movement and this through the link 72 rocks the lever 71 about its stud 70 and contracts the band 67 on the flange 39^a of the drum 39 to clutch the drum 39 to the shaft 37.

It is to be understood that when the drum 39 is thus clutched to the shaft it is rotated bodily with the spider 68 and lever 71. The pulley 75 slips relative to its contracted brake band 76 but the drag exerted by the brake band on the pulley maintains the brake band 67 contracted and the drum 39 effectively clutched to the shaft 37.

For the purpose of rotating the drum 39 in an opposite direction to retract the dipper stick 11 planetary gearing is provided and is of the type shown in prior Patent Number 1,570,108, granted January 19, 1926, to Lewis Wehner. This planetary gearing comprises a driving pinion 77 keyed to the shaft 37 along one side of the drum 39 and meshing with planet gears 78 rotatably mounted

on stud shafts 79 fixed in a carrier 80, having its hub loosely mounted on the shaft 37 and provided with a peripheral flange 81. These planet gears 78 also mesh with an internal ring gear 82 fixed to or otherwise securely mounted upon the drum 39. A planetary brake 83 is cooperatively associated with the flange 81 of the carrier 80 and is controlled in the usual manner. With this arrangement, when the shaft 37 is turning and the planetary brake 83 is released, pinion 77 rotates the planet gears 78 which travel around the internal gear 82 and bodily rotate their carrier 80, since the carrier is unrestrained and free to rotate at this time. However, when the planetary brake 83 is contracted on to the flange 81 of the carrier, the carrier is held and consequently the planet gears 78 cannot move bodily but may only rotate about their studs 79. This rotation of the planet gears 78 rotates the drum 39 in a direction opposite to the rotation of the shaft 37.

In order to hold the drum 39 in any position when both the clutch and planetary gearing associated therewith are released or idle a manually operated brake 84 is operatively associated with the peripheral portion 85 of the drum 39 and may be clamped around such portion or released therefrom. Of course, the brakes 83 and 84 are anchored on the platform in a manner similar to the corresponding brakes in the patent hereinabove mentioned.

A hoist line 86 is provided and has one end secured to and wound around the hoist drum 40 as shown in Figure 1 and passes over a sheave 87 mounted on the boom 6 adjacent its upper and outer end. The hoist line then passes down under a sheave 88 interconnected with the outer end of the dipper stick 11 and bucket 12 as shown in Figure 1, and the hoist line then extends up to the outer end of the boom 6 and is anchored or dead-ended thereon as shown at 89. The drum 40 is clutched to the shaft 37 to rotate therewith when it is desired to elevate the outer end of the dipper stick, that is, to elevate the bucket on the outer end of the dipper stick and the clutch employed for this purpose is preferably the same as the clutch heretofore described in connection with the drum 39, this clutch co-acting with a flange 40^a provided on the drum 40, and utilizing the large gear wheel 36 as its spider. The other parts of this clutch for the drum 40 correspond to similar parts of the clutch provided for the drum 39 and are designated by primed reference numerals. In order to hold the drum 40 in any adjustment it is provided with an annular flange 90 at one end thereof and with this flange 90 a brake 91 is associated, the brake being mounted on the platform and suitably controlled. When the brake 91 is released and the band 67 disengaged from the flange 40^a the bucket

12 lowers under the action of gravity but this action is controlled by the brake 91. The lowering may be accelerated by releasing the clutch and brake of the drum 40 and thrusting the dipper stick 11 outwardly by clutching the drum 39 on the shaft 37. A boom hoist line 92 is provided and has one end secured to and wound on the drum 41. The boom hoist line 92 then passes up over a pulley 93 rotatably mounted on a shaft 94 carried at the upper end of a frame-work 95 as shown in Figures 1, 4 and 5. The hoist line then passes forwardly and upwardly to a sheave 96 carried by a bracket 97 mounted on the boom, traverses the boom to a sheave 98 arranged on the opposite side of the boom from the sheave 96 but located at the same level as the sheave 96. The boom hoist line then passes rearwardly to a sheave 99 mounted on the shaft 94, extends along the shaft 94 to a sheave 100 also mounted thereon, then extends forwardly to sheave 101 mounted on the same axis as the sheave 96 but below the same, then extends through the boom to a sheave 102 mounted on the same axis as the sheave 98 but disposed below the same, and then extends rearwardly to the framing 95 to which it is anchored or dead-ended as at 103.

With the hoist line 92 wound around the drum 41 and reeved as shown, the drum is elevated when the drum 41 is rotated in a direction opposite to the shaft 37, that is, when the drum 41 is rotated in a clockwise direction as viewed in Figure 1. For the purpose of effecting this rotation of the drum 41 planetary gearing 104 is provided between the drum 41 and the shaft 37. This planetary gearing 104 is exactly the same as the planetary gearing employed for the drum 39, and the parts of the gearing 104 corresponding to the parts of the planetary gearing 39 or designated by prime reference numerals. When the boom is to be lowered the drum 41 is permitted to rotate in the same direction as the shaft 37, that is in a counter clockwise direction as viewed in Figure 1 and this movement is controlled by a brake 105. With parts possessing the mass of the boom and the elements carried thereby it is undesirable that the lowering speed of the drum 41 should ever exceed the speed of rotation of the shaft 37 and for this purpose a clutch arrangement is provided between the drum 41 and the shaft 37 to prevent the drum 41 from over-running the shaft 37. This clutch arrangement includes a ratchet 106 keyed to the shaft 37 within the peripheral flange 41 of the drum 41. A pawl 107 is pivoted as at 108 to the drum 41 and coacts with the teeth of the ratchet 106. To automatically disengage the pawl 107 from the ratchet 106 at the proper time whereby to prevent clicking and yet automatically engage the pawl and ratchet when engagement is desirable spring 109 projected friction cups or shoes 109 are car-

ried by the pawl 107 and engage cheek plates 110 fixed to the ratchet 106 and between which the pawl 107 and shoes 109 are positioned. With this pawl and ratchet arrangement when the planetary gearing is operated to rotate the drum 41 in a clockwise direction as viewed in Figure 1, pawl 107 will be disengaged from the ratchet 106 because of the drag which the cheek plates exert on the friction shoes 109. These cheek plates 110 rotate with the ratchet 106 and shaft 37 in a counter clockwise direction and with the drum 41 rotating in a clockwise direction the shoes 109 are pulled by the cheek plates to swing the pawl 107 away from the ratchet 106. However, when the planetary gearing 104 is not operating and the brake 105 released, the weight of the boom and the parts carried thereby causes the drum 41 to operate in a counter clockwise direction, that is in the same direction as the shaft. If the drum 41 rotates so fast as to tend to over-run the shaft 37 the shoes 109 drag on the cheek plates 110 to cause the pawl 107 to engage the ratchet 106 and lock the drum 41 to the shaft 37.

From the foregoing it will be understood that the present invention consolidates all of the drums on a single shaft. Such an arrangement is so compact as to be well adapted to be mounted on the platforms of the small power shovels or so-called "truck type".

Another important advantage resides in the organization with a single shaft carrying a digging drum or sprocket and a hoist drum of a shipper shaft drive of such character that the driving elements are located centrally of the boom. Not only are these advantages had but the shipper shaft drive is a double chain drive exerted through the axis of the boom foot in such a manner that the boom may be raised and lowered without effecting the drive for the shipper shaft. Moreover, by having the chain drive along the boom embodying a sprocket wheel fixed to the shipper shaft between the bearings thereof, the disadvantages inherent in overhung gears are obviated.

The invention claimed is:

1. An excavator crane comprising a platform, a boom pivotally mounted on the platform, a dipper stick mounted on the boom, crowding mechanism mounted on the boom and operatively associated with the dipper stick, a hoist line associated with the boom and operatively associated with the dipper stick, a digging drum, a hoisting drum operatively connected with the hoist line, a single shaft on which the digging drum and hoisting drum are mounted, a sleeve shaft rotatably mounted about the axis of the boom foot, means for rotating said sleeve shaft from the digging drum including a pair of bracket arms adjustably mounted on the axis of the boom foot a shaft rotatably mounted on said bracket arms, a sprocket

wheel fixed to said shaft, a sprocket wheel fixed to the digging drum, a sprocket chain engaged with said sprocket wheels, means coacting with the bracket arms for tensioning the sprocket chain, gearing between the shaft mounted on the bracket arms and the sleeve shaft, and chain and sprocket gearing between the sleeve shaft and the crowding mechanism.

2. A multiple drum assembly for excavator cranes including a single drum shaft, a digging drum, a hoisting drum and a boom hoist drum, all mounted on said shaft, means for clutching the digging drum to the shaft to rotate therewith, planetary gearing for reversely rotating the digging drum from the shaft, means for clutching the hoisting drum to the shaft, means for clutching the boom hoisting drum to the shaft, and planetary gearing for reversely rotating the boom hoisting drum from the shaft.

3. An excavator crane comprising a platform having a boom foot socket, a boom having a foot, a shaft pivotally connecting the boom to the boom foot socket, a shipper shaft, spaced bearings mounted on the boom and receiving the shipper shaft, a sprocket wheel fixed to the shipper shaft between the bearings thereof, a sleeve shaft mounted on the pivot shaft of the boom, a sprocket wheel fixed to the sleeve shaft, a sprocket chain trained over the sprocket wheels, and means for rotating the sleeve shaft in either direction.

4. An excavator crane comprising a platform having a boom foot socket, a boom having a foot, a shaft pivotally connecting the boom to the boom foot socket, a shipper shaft, spaced bearings mounted on the boom and receiving the shipper shaft, a sprocket wheel fixed to the shipper shaft between the bearings thereof, a sleeve shaft mounted on the pivot shaft of the boom, a sprocket wheel fixed to the sleeve shaft, a sprocket chain trained over the sprocket wheels, and means for rotating the sleeve shaft in either direction, and including a digging drum having a sprocket wheel, bracket arms mounted on the pivot shaft of the boom, a shaft mounted on said bracket arms, a sprocket wheel mounted on said last mentioned shaft, a sprocket chain trained over said last mentioned sprocket wheel and over the sprocket wheel of the digging drum, means for swinging said arms to tension said last mentioned sprocket chain, and gears between the shaft mounted on the bracket arms and the sleeve shaft.

5. An excavator crane comprising a platform having a boom foot socket, a boom having a foot, a shaft pivotally connecting the boom to the boom foot socket, a shipper shaft, spaced bearings mounted on the boom and receiving the shipper shaft, a sprocket wheel fixed to the shipper shaft between the bearings thereof, a sleeve shaft mounted

on the pivot shaft of the boom, a sprocket wheel fixed to the sleeve shaft, a sprocket chain trained over the sprocket wheels, and means for rotating the sleeve shaft in either direction and including a digging drum having a sprocket wheel, bracket arms mounted on the pivot shaft of the boom, a shaft mounted on said bracket arms, a sprocket wheel mounted on said last mentioned shaft, a sprocket chain trained over said last mentioned sprocket wheel, and over the sprocket wheel of the digging drum, means for swinging said arms to tension said last mentioned sprocket chains, and gears between the shaft mounted on the bracket arms and the sleeve shaft, said means for swinging the bracket arms to tension the associated sprocket chain including screws pivotally connected to the bracket arms and adjustably connected to the bracket arms and adjustably connected to the platform.

6. An excavator crane comprising a platform, a boom mounted on the platform, a dipper stick mounted on the boom, crowding mechanism mounted on the boom and operatively associated with the dipper stick, a hoist line associated with the boom and operatively associated with the dipper stick, a digging drum, means operated from the digging drum and driving said crowding mechanism, a hoisting drum operatively associated with the hoist line, a boom hoist drum, means controlled by the boom hoist drum for raising and lowering the boom, a single drum shaft mounted on the platform and supporting the digging drum, the hoisting drum and the boom hoist drum and means on said shaft for independently or simultaneously actuating said drums from said shaft.

7. An excavator crane comprising a platform, a boom mounted on the platform, a dipper stick mounted on the boom, crowding mechanism mounted on the boom and operatively associated with the dipper stick, a hoist line associated with the boom and operatively associated with the dipper stick, a digging drum, means operated from the digging drum and driving said crowding mechanism, a hoisting drum operatively associated with the hoist line, a boom hoist drum, means controlled by the boom hoist drum for raising and lowering the boom, a single drum shaft mounted on the platform and supporting the digging drum, the hoisting drum and the boom hoist drum, means for constantly rotating the single drum shaft, and independent means for actuating each of the drums from the drum shaft.

8. A drive for the shipper shaft of an excavator crane including a platform and a boom on the platform and on which the shipper shaft is mounted and comprising a digging sprocket wheel, a shaft, a sprocket wheel fixed to said shaft, a chain extending around said sprocket wheels, bracket arms support-

- ing said shaft for movement about the axis of swing of the boom, means for adjusting said bracket arms and holding them in adjusted position to tension said sprocket chain, and means for taking motion from said shaft and transmitting motion through the axis of swing of the boom to the shipper shaft.
9. A drive for the shipper shaft of an excavator crane including a platform and a boom on the platform and on which the shipper shaft is mounted and comprising a digging sprocket wheel, a shaft, a sprocket wheel fixed to said shaft, a chain extending around said sprocket wheels, bracket arms supporting said shaft for movement about the axis of swing of the boom, means for adjusting said bracket arms and holding them in adjusted position to tension said sprocket chain, and means for transmitting motion from the shaft to the shipper shaft, and including a sleeve shaft mounted for rotation about the axis of the boom foot and geared to said shaft, and chain and sprocket gearing between the sleeve shaft and the shipper shaft.
- 25 10. An excavator crane comprising a platform, a boom mounted on the platform, a dipper stick mounted on the boom, crowding mechanism mounted on the boom and operatively associated with the dipper stick, a hoist line associated with the boom and operatively connected to the dipper stick, digging and hoisting drums supported on the platform for rotation about a common axis, said hoisting drum being connected with said hoisting line and being arranged transversely of the platform in approximate fore and aft alinement with the boom whereby the hoisting line will not be excessively deflected in extending from the hoisting drum to the boom, chain and sprocket gearing drive means extending between the crowding mechanism and the axis of swing of the boom at the foot thereof, chain and sprocket gearing actuated from the digging drum and extending to a point adjacent to but offset from the foot of the boom, and a driving connection between said chain and sprocket gearings.
- 40 11. An excavator comprising a platform, a boom swingably supported on the platform, a dipper stick mounted on the boom, crowding mechanism mounted on the boom and operatively associated with the dipper stick, said crowding mechanism including a shipper shaft, spaced bearings on the boom for the shipper shaft and gearing between the shipper shaft and the dipper stick, a hoisting line extending out over the boom and connected to the dipper stick, digging and hoisting drums supported for rotation on said platform and about a common axis, said hoisting line being connected to said hoisting drum, said hoisting drum being arranged in approximate fore and aft alinement with the boom whereby said hoisting line will be but
- 55 60 65

slightly deflected in traveling from the hoisting drum out over the boom, and a double chain shipper shaft drive means actuated from the digging drum and exerted along the platform in offset relation to the boom and then carried around the axis of the boom foot and centrally along the boom and applied to the shipper shaft in between its spaced bearing.

In witness whereof, we hereto affix our signatures.

HOLGER L. MITCHELL
